UNITED STATES PATENT OFFICE.

JOHN FREDERICK SCHMIDT, OF BLUE EARTH CITY, MINNESOTA.

CLOTHES-DRIER.

SPECIFICATION forming part of Letters Patent No. 502,913, dated August 8, 1893.

Application filed October 22, 1891. Renewed April 10, 1893. Serial No. 469,856. (No model.)

To all whom it may concern:

Be it known that I, JOHN FREDERICK SCHMIDT, a citizen of the United States, residing at Blue Earth City, in the county of Faribault and State of Minnesota, have invented 5 certain new and useful Improvements in Clothes-Driers; and I do hereby declare the following to be a full, clear, and exact description of the invention, such as will enable others skilled in the art to which it appertains to make and use the same.

My invention relates to improvements in clothes driers and it has for its object to provide a simple and inexpensive apparatus for 15 supporting lines on which the clothes can be suspended for drying purposes.

With these ends in view my invention contemplates a ground box adapted to be sunk into the earth, a post fitted in said box and 20 having a socket in its upper end, a cap for said post to protect the same, a washer in the bottom of said socket and a supporting pole, carrying radial arms fitted in said socket and adapted to turn easily therein on the washer.

25 My invention consists further of certain details of construction and arrangement of parts as will more fully appear hereinafter.

To enable others to more readily understand my invention, I have illustrated the 30 same in the accompanying drawings, in which—

Figure I represents an elevation of my improved drier with the arms extended, partly in section. Fig. II is a view in elevation with 35 the arms folded. Fig. III is a side view of one of the arms having the single slots therein. Fig. IV is a perspective view of the arm having the double slots, and Fig. V is a bottom plan view of said arm.

40 Referring to the drawings, in which like letters denote corresponding parts in all the figures, A designates the ground box which may be sunk in the earth or arranged in a suitable box or support as desired, and when 45 the clothes drier is not in use the box is covered in a suitable manner. A post B is inserted in an opening a in the ground box, and this post forms a firm and solid base for the supporting pole C which fits snugly in a 50 socket b in said post. Both the ground box and post B may be provided with holes at the bottom of the openings a and b to permit any

water or dirt to be discharged, and the upper end of the post is preferably provided with a metallic cover b' to prevent the post from rotting, &c. A washer b'' is placed in the bottom of the socket b to prevent the same from 55 wearing.

On the upper end of the pole C is secured a ring or band D and it has a series of integral projections d to which the supporting braces E are pivoted. Another ring F is arranged on the supporting pole and adapted to slide thereon, and it has divided projections f. The arms G and the main arm I' 60 are pivotally secured between the projections f, and the braces E are also pivotally secured to the arms at a suitable point, on each side thereof. A rope H is fastened to projecting lips h only one of which is shown 65 on the drawings on opposite sides of the ring F and this rope runs over a pulley h' supported on the top of the pole C. This rope and the supporting braces are of such length that when the drier is folded, they will both 70 remain taut and the rope will serve as a more direct support for the slidable ring.

The clothes line I is composed of one continuous piece which is run around the drier through slots in the arms to the starting 80 point and then reversed, and this is continued until the drier is completed. A knot is first tied in the line and it is then run through a slot i in the main arm I', shown in Figs. IV and V. In each of the other arms is a series 85 of slots J which extend in a slanting direction and terminate in an eye j which is out of line with the opening of said slot. These slots are covered by spring catches i' which have their ends turned downward and 90 the line I can be readily slipped under said end and into its proper position in the eye forming a part of each slot. In the main arm I' the slots extend diagonally across the arm and have the eyes j' above and below the slot 95 to receive the clothes line. The rope starts from the end of the arm I' and runs around the drier back to said arm, where it passes through the lower eye of the slot and down and through the upper eye of the next slot 100 below. This operation is completed until the clothes line is completely strung. By this arrangement of the slots the line can be adjusted at any time so that the bent portions

thereof will not rot, nor can it rust as it is not in contact with any metal, and it can be readily tightened as desired. When the drier has been properly adjusted a pin K is inserted 5 in a hole in the pole beneath the slideable ring, and stops k are provided above said band to prevent it from going too high.

I am aware that changes in the form and proportion of parts and details of construction can be made without departing from the spirit or sacrificing the advantages of my invention, and I therefore reserve the right to make such changes as fall within the scope of my invention.

Having thus described my invention, what I claim as new, and desire to secure by Letters Patent, is—

In a clothes drier, the ground box A adapt-

ed to be sunk into the earth, the post B fitted in said ground box and having the socket b 20 in its upper end, said post and ground box having horizontal openings at the bottom of the sockets therein to permit foreign matter to be discharged, a metallic cap b' arranged over the upper edge of the post B to protect 25 the same, a washer b'' in the bottom of the socket b and the supporting pole C, carrying the radial arms, fitted in said socket and adapted to turn easily therein on the washer, substantially as described.

In testimony whereof I affix my signature in presence of two witnesses.

J. FREDERICK SCHMIDT.
